US00D801719S

(12) **United States Design Patent** (10) **Patent No.:** **US D801,719 S**
(45) **Date of Patent:** **** Nov. 7, 2017**

(54) **CHAIR**

(71) Applicant: **Vitra Patente AG**, Birsfelden (CH)

(72) Inventor: **Alberto Meda**, Milan (IT)

(73) Assignee: **VITRA PATENTE AG**, Birsfelden (CH)

(**) Term: **15 Years**

(21) Appl. No.: **29/573,939**

(22) Filed: **Aug. 10, 2016**

(30) **Foreign Application Priority Data**

May 13, 2016 (WO) DM/090703

(51) **LOC (10) Cl.** **06-01**

(52) **U.S. Cl.**

USPC **D6/366**
